UNITED STATES PATENT OFFICE

91,677

DESIGN FOR A BOTTLE

Herman L. Luly, Alton, Ill., assignor to Continental Drug Corporation, Alton, Ill., a corporation of Illinois

Application December 14, 1933, Serial No. 50,069

Term of patent 3½ years

To all whom it may concern:

Be it known that I, HERMAN L. LULY, a citizen of the United States, residing at Alton, county of Madison, State of Illinois, have invented a new, original, and ornamental Design for a Bottle, substantially as shown in the accompanying drawing, in which—

Fig. 1 is a top plan view showing my new design.

Fig. 2 is a front elevation.

Fig. 3 is a side elevation.

I claim:

The ornamental design for a bottle, substantially as shown.
